CLAUDE L. MATTHEWS, OF ST. LOUIS, MISSOURI, ASSIGNOR TO W. N. MATTHEWS AND BROTHER, A COPARTNERSHIP COMPRISING HIMSELF AND WM. N. MATTHEWS, OF ST. LOUIS, MISSOURI.

GROUND-ANCHOR.

1,142,347.

Specification of Letters Patent.

Patented June 8, 1915.

Application filed October 31, 1912. Serial No. 728,966.

To all whom it may concern:

Be it known that I, CLAUDE L. MATTHEWS, a citizen of the United States, residing at city of St. Louis, State of Missouri, have invented a certain new and useful Improvement in Ground-Anchors, of which the following is a full, clear, and exact description, such as will enable others skilled in the art to which it appertains to make and use the same, reference being had to the accompanying drawings, forming part of this specification, in which—

Figure 1 is a side elevational view of my improved ground anchor. Fig. 2 is a sectional view on line 2—2 of Fig. 1. Fig. 3 is a vertical sectional view. Fig. 4 is a top plan view with the flukes extended to their anchoring position. Fig. 5 is a sectional view on line 5—5 of Fig. 1. Fig. 6 is a side elevational view of a modified form.

This invention relates to a new and useful improvement in ground anchors, the object being to construct a simple and cheap device of the character described and one which can be buried in the ground and have its flukes forced outwardly so as to afford a greater amount of resistance to the pull on the guy rope connected thereto.

Ground anchors of the character described are employed for various purposes, a common use being for the attachment of guy rope employed in connection with telegraph, telephone and lighting poles.

In the drawings, 1 indicates the guy rod which, in practice, is usually provided with an eye at its upper end, not shown, to which eye is connected the guy rope. The lower end of this rod is threaded to receive a nut 2.

3 indicates a casting, the base portion of which is preferably in the form of a hollow ring from which rises two walls 4 connected at their upper ends by a conical shaped boss 5 through which the guy rod 1 passes.

6 is a connecting rib between these walls formed by the seat for the nut 2 and with an opening through which passes the lower end of the guy rod 1. The purpose in thus providing a seat for the nut is to enable the guy rod to be unscrewed and detached from the anchor in the event that it is desired to no longer use the anchor. The side walls are separated by a slot 7 on each side of which are grooves 8.

9 are the plates or flukes of the anchor,

the upper ends of which are slightly thickened, as at 10, to form hammering heads.

11 indicates a lug on the inner face of each fluke near its upper end which fits into the groove 7 and has a dovetailed relation thereto. The plates 10 are bilaterally symmetrical with respect to their lugs 11, and thus when said plates are properly mounted on the base they occupy positions directly opposite to each other, and their side portions extend outwardly at equal distances from a line drawn through the center of the rod 1, and the centers of the slot 7. By virtue of this construction the strains resulting from the pull of the guy rope attached to the rod 1 are equalized throughout the anchor, and consequently uniformly transmitted to the earth in which the anchor is embedded. On each side of lug 11, the flukes are provided with ribs 12 which fit into the grooves 8 and guide the flukes in their downward and outward movement.

In operation the parts are assembled as shown in Fig. 1, the flukes being held in their elevated position by means of a string 13. The hole to receive the anchor may be formed by an ordinary post hole digger to the required depth depending upon the purpose for which the anchor is to be used and the nature of the ground. The guy rod is assembled and the anchor lowered to the bottom of the hole. When at the bottom of the hole, a suitable implement, such as a tamping bar, is employed to drive in the flukes downwardly and outwardly by striking them upon their hammering heads 10. The string 13, of course, will be quickly broken and permit the flukes to move from the position shown in Fig. 1 to the position shown in Fig. 3. The earth is tamped above the anchor and around the rod and the guy rope attached to the eye in the guy rod.

In order that the walls 4 may more effectively resist the pull on the guy rod, the same are preferably formed of a series of steps 4^a, as shown in Fig. 5. These steps provide shoulders which engage the material tamped on and around the anchor and are particularly effective when broken stones are employed.

In Fig. 6, I have shown a modified form in which there is a ring 13^a slidingly mounted on the guy rod and connected by links 14 to the flukes. In this manner both flukes are

connected together and can be driven downwardly and outwardly in unison by striking the ring with the tamping tool.

I claim:

5. 1. In a ground anchor, a base having a pair of oppositely disposed curved faces in each of which is formed a vertically disposed dove-tailed slot, curved plate flukes arranged for sliding movement on said curved faces, 10 and a dove-tailed lug on the rear face of each fluke, which lug is arranged for sliding movement in the corresponding dove-tailed groove, said base being provided with a pair of oppositely disposed curved faces between 15 the first mentioned pair of curved faces, and the second mentioned pair of curved faces being provided with horizontally disposed shoulders.
2. A ground anchor comprising a base 20 having a pair of oppositely disposed curved faces in each of which is formed a vertically disposed slot and a groove and a pair of flukes arranged for sliding movement on said curved faces, each fluke being provided 25 on its rear side with ribs which engage the corresponding slot and groove.
3. A ground anchor comprising a base having a pair of oppositely disposed curved faces which are provided with horizontally 30 disposed ribs or corrugations, said base also having a pair of oppositely disposed vertically curved faces, each of which is pro-

vided with a centrally arranged dove-tailed slot and a pair of adjacent grooves, a curved fluke arranged for sliding movement upon 35 each curved face, a dove-tailed lug projecting rearwardly upon each fluke through the corresponding slot, and ribs formed on the rear side of each fluke, which ribs engage in the grooves adjacent the slot. 40

4. A ground anchor comprising a base having a pair of oppositely disposed curved faces which are provided with horizontally disposed ribs or corrugations, said base also having a pair of oppositely disposed vertically curved faces, each of which is provided with a centrally arranged dove-tailed slot and a pair of adjacent grooves, a curved fluke arranged for sliding movement upon 45 each curved face, a dove-tailed lug projecting rearwardly from each fluke through the corresponding slot, ribs formed on the rear side of each fluke, which ribs engage in the grooves adjacent the slot, and hammering 50 heads integral with the upper ends of said flukes. 55

In testimony whereof I hereunto affix my signature in the presence of two witnesses, this 28th day of October, 1912.

CLAUDE L. MATTHEWS.
